Primary Examiner—Doris Clark

Attorney, Agent, or Firm—Baker & Daniels[57] **CLAIM**

The ornamental design for a window molding extrusion, as shown and described.

DESCRIPTION

FIG. 1 is a perspective view of a window molding extrusion illustrating my new design;

FIG. 2 is a perspective view of the window molding extrusion of FIG. 1 shown installed on the perimeter of window of a residential structure; the broken lines are for environmental purposes only and form no part of the claimed design;

FIG. 3 is a front view of the window molding extrusion shown in FIGS. 1 and 2;

FIG. 4 is a rear view thereof;

FIG. 5 is a cross-sectional view of uniform proportions of the window molding extrusion shown in FIGS. 1 through 4 taken along sectional lines 5—5 of FIG. 3; and,

FIG. 6 is a top plan view of the window molding extrusion shown in FIGS. 1 through 5.
